C. J. HUG

DISTRIBUTOR FOR CONCRETE MIXERS

Filed Nov. 22, 1923

INVENTOR CHRISTIAN J. HUG,
by James L. Hopkins, Attorney.

UNITED STATES PATENT OFFICE.

CHRISTIAN J. HUG, OF HIGHLAND, ILLINOIS, ASSIGNOR TO THE HUG COMPANY, OF HIGHLAND, ILLINOIS, A CORPORATION OF ILLINOIS.

DISTRIBUTOR FOR CONCRETE MIXERS.

Application filed November 22, 1923. Serial No. 676,433.

To all whom it may concern:

Be it known that I, CHRISTIAN J. HUG, a citizen of the United States of America, residing at Highland, in the county of Madison and State of Illinois, have invented certain new and useful Improvements in Distributors for Concrete Mixers, of which the following is a specification, reference being had therein to the accompanying drawing.

10 My invention relates to improvements in distributors for concrete mixers, and has for its object to provide mechanism for receiving the discharge from the mixer, elevating the material so received, and discharging the same into a suitable vehicle. The invention is adapted for use where it is desired to deposit the mixed concrete in place at variable distance from the mixer, as in road building.

In the drawings—

20 Fig. 1 is a side elevation of an apparatus embodying my invention.

Fig. 2 is a front elevation of the same, parts being broken away.

25 In the embodiment of my invention shown in the drawings the concrete mixing mechanism 3 is carried on sills 4 provided with wheels 5. The sills 4 support the uprights 6 and 7 the top beam 8 and horizontal, forwardly extending beam 9. The inclined brace 10 is secured to the beams 8 and 9.

30 Surmounting the frame so formed is the fixed arm 11 suitably perforated to receive the hook 12 and the block 13.

35 Co-operating with the block 13 is the block 14 having a hook 15 to engage the eye 16 on the bail 17.

40 The bucket 18 has the transverse shaft 19 secured to its bottom, said shaft 19 carrying at its ends the guide-rollers 20—20, which 45 guide-rollers 20 fit within the channelled guide 21; said guide 21 having the lower extension 22 secured thereto by the hinge 23. When said extension 22 is in its operative position its lower end is in contact with the surface 24 whereon the concrete mixer rests, and is held in such position by the hook 25, as shown in Fig. 1, in which position said hook 25 engages a hole 26 in the sill 4. When the apparatus is to be moved 50 said hook 25 will be disengaged from said sill 4 and engaged with the hole 27 in the upright 7, thus bringing the lower end of the extension member 22 (which is channelled to correspond with the guide 21) out

of contact with the surface supporting the 55 wheels 5.

It is essential to the mode of operation of my device that the guide-rollers 20—20 be at all times seated in the channelled guide 21.

At or near the top of the bucket 18 and 60 at each side thereof is a guide-roller 28 which is arranged to ride in the channel of the curved channelled guide-member 29.

The bucket 18 being filled, a pull on the rope 30 will operate through the blocks 65 13—14 to raise said bucket 18 to the elevated and dumping position illustrated by means of dotted lines in Fig. 1, in which position the content of said bucket 18 is discharged into a suitable vehicle 31 for removal to its 70 place of ultimate deposit.

The guide-members 21—29 are secured in place by being attached to the beam 9 and brace 32.

75 The content being discharged from the bucket 18 the rope 30 is relaxed to permit the bucket 18 to fall back to its lowermost and receptive position.

Various structural modifications of the device as illustrated and above-described may 80 be made without departing from my invention, whose objects will be accomplished by any suitable guiding and elevating means to raise the bucket-content from the point at which it was received from the discharge-spout 33, to a point where, being tilted, it will be discharged into a suitable distributing vehicle.

85 Having thus described my invention, what I claim as new, and desire to secure by Letters Patent, is—

1. In a distributor for concrete mixers a bucket having a shaft secured to its bottom; 90 guide-rollers mounted on the ends of said shaft; a channelled guide-member and a hinged lower extension thereof wherein said guide-rollers travel; other guide-rollers mounted on the sides of said bucket; a channelled guide-member arranged to receive said last-named guide-rollers; a bail affixed to said shaft and arranged to draw the bucket upwardly, its guide-rollers traveling in said 95 guide-members, and tilting said bucket to 100 discharge its contents.

2. In a distributor for concrete mixers a bucket having a shaft secured to its bottom; guide-rollers mounted on the ends of said shaft; a channelled guide-member and a 105

hinged lower extension thereof wherein said guide-rollers travel; the lower extension of said guide-member contacting when in operative position with the surface supporting the distributor and being hinged to be drawn out of contact with said surface when the apparatus is to be moved; other guide-rollers mounted on the sides of said bucket; a channeled guide-member arranged to re-

ceive said last-named guide-rollers; a bail affixed to said shaft and arranged to draw the bucket upwardly, its guide-rollers traveling in said guide-members, and tilting said bucket to discharge its contents.

In testimony whereof I have hereunto affixed my signature.

CHRISTIAN J. HUG.
